UNITED STATES PATENT OFFICE.

ELNO H. TRUMP, OF BARBERTON, OHIO, ASSIGNOR TO THE LAMBERT TIRE & RUBBER COMPANY, OF BARBERTON, OHIO, A CORPORATION OF OHIO.

DESIGN FOR AN ELASTIC VEHICLE TIRE.

Application filed January 22, 1920. Serial No. 353,340. Term of patent 3½ years.

To all whom it may concern:

Be it known that I, ELNO H. TRUMP, a citizen of the United States, residing at Barberton, in the county of Summit and State of Ohio, have invented a new, original, and ornamental Design for Elastic Vehicle Tires, of which the following is a specification, reference being had to the accompanying drawings, forming a part thereof.

Figure 1 is a plan view of a portion of an elastic vehicle tire, showing my new design, and,

I claim:

The ornamental design for an elastic vehicle tire as shown.

ELNO H. TRUMP.
